LIPSTICK HOLDER

Jan de Swart, Los Angeles, Calif., assignor of one-half to C. Bland Jamison, Beverly Hills, Calif.

Application July 24, 1943, Serial No. 496,025

3 Claims. (Cl. 206—56)

My invention has to do with holders and has for one of its more particular objects the provision of a tubular housing, a slidable carrier and an operating member so arranged and constructed that the article being held, such for instance as a lipstick, may be readily projected for use and the housing may be effectively sealed when not in use.

Another object is to provide a lipstick holder which may be economically manufactured and assembled and which is very durable.

An additional object is the provision of a lipstick holder capable of being molded entirely of such materials as synthetic plastics and in which all metal parts may be eliminated.

Still further advantages are provided by my invention and how those as well as the objects hereinabove set forth are achieved will be best understood from the following detailed explanation of a presently preferred embodiment, for which purpose I shall refer to the accompanying drawing, in which:

Fig. 1 is a perspective of the device in closed or inoperative position;

Fig. 2 is a perspective, with part broken away for illustrative purposes, showing the device in course of being opened;

Fig. 3 is a perspective showing the device in a stage intermediate of its open and closed positions;

Fig. 4 is a vertical section, with some parts in elevation, showing the device in operative position;

Fig. 5 is a section on line 5—5 of Fig. 4;

Fig. 6 is a longitudinal medial section of Fig. 1;

Fig. 7 is a section on line 7—7 of Fig. 6; and

Fig. 8 is a side elevation of the housing element.

Referring now to the drawing, I show at 5 a tubular housing having an open top end 6 and a bottom end closed by end cap 7. A longitudinal slot 8 is provided through the side wall of the housing, the housing having at each side of the slot and extending outwardly flush with the respective walls of the slots a flange member 10. Slidable longitudinally in the housing there is a carrier 15 atop which is secured a lipstick L. The bottom portion of the carrier is transversely split at 16 to divide the lower end of the carrier into two legs 15a, 15b, each of which is provided with an inwardly opening recess 17 in its inner face. Each of the recesses 17 opens through the side wall of the carrier opposite the slot 8.

An operating and sealing member generally designated by the numeral 20 has a lower right angle end portion 21 presenting trunnions 22

journaled in the respective recesses 17. Member 20 has a side arm 23 which snugly and laterally engages in the slot 8 between the flanges 10 whereby to effectively seal the slot when the device is not in use, and has an integrally formed cupped end cap 24 to effectively seal the upper end of the housing when the device is not in use (Fig. 1).

To assemble the device, the member 20 is first 10 assembled in the carrier 15 and said carrier assembly is inserted from the lower end of the housing before the end cap 7 is applied. After the carrier assembly is thus inserted, the end cap 7 is secured in place. For instance, the body may 15 be molded of a suitable thermoplastic, such as "Tenite," and acetone may be used to secure the cap 7 in place. Inasmuch as the recesses 17 open at the side of the carrier opposite the slot 8, the trunnions cannot escape therefrom in use.

20 To use my device, starting with the closed or inoperative position shown in Figs. 1, 6 and 7, the cap 24 is lifted sufficiently to clear its side flanges from engagement over the end of the housing (Fig. 2), and then the arm 23 with its 25 carried cap 24 is swung outwardly to the position of Fig. 3, after which the arm 23 is moved upwardly along the slot until it contacts the end wall 27 of the slot (Fig. 4). In this position, the lipstick L is projected into a position for 30 convenient use. After use, the arm is moved downwardly along the slot 8, being swung upwardly before it reaches the end cap 7, and the cap 24 is fitted over the open end of the tubular housing.

From the foregoing it will be observed that 35 only a single slot in the side wall of the tubular body is required and that slot is effectively closed by the arm 23 when the device is not in use to prevent undue exposure of the lipstick to the elements. The flanges 10 enhance this sealing and 40 at the same time provide substantial support and bearing surface for the arm when in use to materially strengthen the device.

While I have described my invention as a holder 45 for lipsticks, it will be understood, of course, that it is susceptible of other uses, and within its broader aspects the invention is capable of being carried out by structures having physical characteristics differing from the details hereinabove particularly described.

50 I claim:

1. A holder comprising a tubular housing having a longitudinal slot through its side wall, a carrier mounted to slide longitudinally in the housing, said carrier having a bifurcated bottom end 55 presenting two depending legs, a laterally and in-

wardly opening recess in each leg, and means for sliding the carrier including an arm laterally engageable in the slot, said arm having a right angle portion presenting trunnions rotatably disposed in said respective recesses.

2. A holder comprising a tubular housing having a longitudinal slot through its side wall, outwardly disposed longitudinal flanges on the housing flush with the respective side walls of the slot, a carrier mounted to slide longitudinally in the housing, said carrier having a pair of spaced parallel depending legs, a recess in each leg opening through the side of the leg opposite the slot and inwardly towards the other leg, and means for sliding the carrier including an arm having sealing engagement with said flanges, said arm having an angular lower end portion presenting trunnions slidably and rotatably engaging in said respective recesses and an angular upper end

portion having sealing engagement with the upper end of the housing.

3. A lipstick holder comprising a tubular housing having a longitudinal slot through its side wall, outwardly disposed longitudinal flanges on the housing, the adjacent faces of the flanges being disposed flush with the respective side walls of the slot, a carrier mounted to slide longitudinally in the housing and means for sliding the carrier including an arm pivotally secured at its lower end to the carrier for lateral swinging movement through the slot, a closure cap carried by the free end of the arm for sealing engagement over the top end of the housing, the side faces of the arm having frictional longitudinal sealing engagement with the flanges when the closure cap is in sealing engagement with the top end of the housing.

JAN DE SWART.
